METHOD OF MAKING ABRASIVE BELTS

James Howard Baker, Green Island, N. Y., assignor to Behr-Manning Corporation, Troy, N. Y., a corporation of Massachusetts

Application October 29, 1937, Serial No. 171,663

1 Claim. (Cl. 51—278)

The invention relates to abrasive belts and to a method of manufacture thereof.

One object of the invention is to provide a cheaper way of making abrasive belts. Another 5 object of the invention is to provide a method of manufacture whereby several belts may be made in one operation.

The invention accordingly consists in the features of construction, combinations of elements, 10 arrangements of parts, and in the several steps and relation and order of each of said steps to one or more of the others thereof, all as will be illustratively described herein, and the scope of the application of which will be indicated in 15 the following claim.

In the accompanying drawing showing one of many possible embodiments of the mechanical features of this invention,

Figure 1 is a vertical sectional view through 20 certain apparatus for manufacturing belts according to the present invention;

Figure 2 is a perspective view of another apparatus used in the production of belts according to the invention;

25 Figure 3 is a plan view of the belts at one stage in their manufacture;

Figure 4 is a perspective view of a plurality of belts just before separation, and

Figure 5 is a view showing the final articles.

30 Referring first to Figure 1, upon any suitable support such as the top of a work bench 10, I provide the apparatus shown in Figure 1. I provide a shaft 11 journalled in bearings in a pair of supports 12 affixed to the bench 10. In the 35 case of the journal supports 12, as in the case of other journal supports, only one thereof is shown since Figure 1 is a sectional view.

Upon the shaft 11, I mount a roll 13 holding 40 a supply of coated abrasive material 14 which is wound upon the roll 13. The coated abrasive material may be of any desired sort. For example, the abrasive may consist of aluminum oxide, silicon carbide, garnet, quartz, emery or the like, and the backing may consist of paper or 45 cloth of any variety or combination of paper and cloth. The bond may be and usually is glue but other bonds such as waterproof bonds and resinous bonds may be provided.

I further provide a roller 15 mounted in journals provided in supports 16 affixed to the bench 10. I further provide a large diameter metal roll 17 mounted in journals in journal supports 18 affixed to the bench 10. I further provide an idler roll 19 mounted in journals in journal supports 20 affixed to the bench 10. I further pro-

vide a take-up roll 21, preferably made of wood and similar to the roll 13, mounted on a shaft 22 which is journalled in journals in a journal support 23 affixed to the bench 10. Secured to the shaft 22 is a large pulley 24. The pulley 24 is 5 driven by a belt 25 passing around a small pulley 26 on the armature shaft 27 of a motor 28 which is likewise affixed to the bench 10.

The operator pulls off some of the coated abrasive material 14a from the roll 14, winding it 10 around the take-up roll 21, and securing it in place by means of a removable bar 30. When the motor 28 is energized, as by means of a switch 31, the take-up roll 21 will be revolved, thus tending to fill up the take-up roller with coated 15 abrasive material 14a which is drawn from the roll 14 of coated abrasive material which was initially provided.

I further provide a standard 32 fastened to the bench 10 and braced thereto by a brace 33. A 20 bell crank lever 34 is mounted upon a shaft 35 which is fastened to the standard 32 by means of brackets 36. This bell crank lever 34 has a forked portion 37 in the front thereof in which is mounted a second bell crank lever 38 pivoted 25 on a pin 39 passing through the forked portion 37. The second bell crank lever 38 has a front forked portion 40 in which is journalled a scoring disk 41 mounted on a pin 42.

For primary adjustment, I provide a screw 43 30 having a knurled portion 44 which is in threaded engagement with the upper end of the bell crank lever 34 and abuts the front surface of a cross member 45 attached to the standard 32. For secondary adjustment, I provide a screw 46 in 35 threaded engagement with the upper end of the bell crank lever 40 and abutting a front surface of the bell crank lever 34.

The scorer 41 consists of a steel disk with a V shaped periphery 48. 40

The coated abrasive material 14 is wound with the abrasive on the outside. The rollers 15 and 19 serve to keep it in peripheral engagement with the roller 17 which acts as an anvil. As the strip of coated abrasive 14a is drawn off the roll 14, it passes under the cutting V edge 48 of the scorer 41 and is scored. When a considerable portion has been wound upon the roll 21, too high speed of drawing the material 14a is prevented by slippage of the belt 25. In other 50 words, the natural tendency of any direct winding mechanism, being to speed up as the take-up roll is wound, is offset by the fact that a friction drive is provided. I preferably provide bolts 50 to secure the motor 28 in place which pass 55

through long slots 51 in the motor base whereby the tension on the belt 25 may be adjusted.

By means of the apparatus shown, a roll of coated abrasive material 14 may be scored. I adjust the screws 43 and 46 so that the backing of the coated abrasive material will not be entirely broken or severed; there is just sufficient strength left to hold the two portions together. Instead of dividing the coated abrasive material into two parts, as shown, I may provide additional scorers 41 and associated mechanism and split the coated abrasive material into three, four, five or more parts. I prefer, however, to score it in one or two places so that it will split into two or three parts.

I now cut the material 14a into suitable lengths on the bias at any desired angle. I prefer an angle of 45°, as indicated in Figure 3.

I now take a piece of material 14b which has been scored as indicated by the line 60 and cut to non-rectangular form with 45° and 135° corners, as shown, and remove some of the abrasive at one end with the apparatus shown in Figure 2. This comprises a flat surface 61 of a bench or table, which may be a portion of the bench 10 if desired, and upon which is mounted a motor 62. The motor 62 is secured to a bracket 63 which has a clamp 64 to clamp it thereto. The bracket 63 has trunnions 65 trunnioning it to the table 61, the trunnions 65 fitting in journal brackets 66. I provide an elevating screw 67 with a hand wheel 68 which is in threaded engagement with the outer end of the bracket 63. I provide a hold down screw 69 which is in threaded engagement with the table 61 and passes through the bracket 63. By this means the motor can be raised and lowered.

The motor armature shaft 70 has secured thereon a grinding wheel 71. This wheel is preferably of aluminum oxide bonded with ceramic bond and of hard grade hardness, but other types of grinding wheels may be used. I provide a straight edge 74 against which the end of the material 14b may rest.

The operator passes the scored material 14b under the grinding wheel, as shown in Figure 2, which rips off the abrasive material therefrom, together with most of the glue or other adhesive, leaving at that point just the backing. In order

to remove as much and no more than desired, the wheel 71 may be raised or lowered by the means for raising and lowering the motor 62 described.

The material 14b is now in the form shown in Figure 3 with a scored line 60 therein and a portion 75 from which the abrasive has been removed. The operator now with a brush places glue upon the portion 75, then bends the material 14b into the form of a belt with abrasive on the outside. After the end of the belt is glued, it is lapped to the other end and the joint is pressed by a suitable clamp or pressure device. The material is now in the form shown in Figure 4, in which a pair of belts 14c and 14d are held together at the scoring line 60. These belts may be readily broken apart into two separate belts 14c and 14d, as shown in Figure 5. The advantage of the method of procedure is that for a single abrasive removing operation and a single gluing operation, two, three or four belts may be made where one belt was made before. For certain long belts, I prefer an angle of 45°, as shown in Figure 3. For belts which are relatively short in length as compared with their width, a wider angle is preferably used, such as for example an inside angle of 70° at the acute corners.

It will thus be seen that there has been provided by this invention a method and an article in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

I claim:—

Method of making several abrasive belts at one time which comprises providing a roll of coated abrasive material, drawing the abrasive material under a scorer, cutting the abrasive material to the desired length, joining the two ends together, and separating the wide belt into multiple narrower belts by separating along the scored lines.

JAMES HOWARD BAKER.
